COMBINED SUCKER ROD COUPLING AND GUIDE

Filed Sept. 10, 1937

UNITED STATES PATENT OFFICE

2,162,426

COMBINED SUCKER ROD COUPLING AND GUIDE

Jeremiah J. Fitzpatrick, Oklahoma City, Okla.

Application September 10, 1937, Serial No. 163,319

10 Claims. (Cl. 255—28)

This invention relates to improvements in my former Patent No. 1,995,095 issued March 19, 1935. In this patent there is provided a structure in the nature of a sucker rod coupling of integral construction, which when positioned between the joints of a sucker rod in a pumping well will not interfere with the flow of fluid therein but will function to effect the removal of accumulating paraffin, act as a guide to space the sucker rod from the tubing thereby eliminating wear, prevent the slap of the rod within the tubing upon reversal of the motion of the rod, and function in initiating the lift of the oil upon the upward movement of the rod, whereby the rod strain is materially equalized and the travelling valve is relieved of a portion of its load.

It has been determined that where the structure in question is subjected to long and excessive wear sufficient to reduce the thickness of the spaced webs that in some instances the coupling will rupture at this point, i. e., the spaced webs will shear thereby making a fishing operation necessary.

The object of this invention is to provide means for quickly retrieving the lost rod sections without the use of special or expensive tools.

More specifically this invention comprehends the provision of an internally threaded portion so situated in the sucker rod coupling assembly that it will be at all times accessible for engagement with a tap.

A further object of this invention resides in the provision of means for keeping the internally threaded sections clean of sediment, scale or sand so that the engagement of the tap can be quickly and conveniently accomplished.

Reference will be had to the accompanying drawing forming a part of this specification and wherein like numerals of reference designate corresponding parts throughout the several views, in which—

Fig. 1 is a side elevation showing the invention positioned within the tube, the latter being in section.

Fig. 2 is a side elevation partly in section of a portion of a coupling enlarged to clearly disclose the invention.

Fig. 3 is a side elevation of a fragment of this structure and

Fig. 4 is a section on line 4—4 of Fig. 3.

In Fig. 1 the tube is indicated by reference character A and the sucker rod section by the reference character B. The extremities of the sucker rod sections are screw threaded to provide

threaded pins C which are received within the internally threaded boxes provided at the end of the coupling structure, which latter embodies the present invention. The coupling assembly is shown as an integral body and includes an intermediate tubular portion 10 and coupling elements 11 and 12. The coupling elements 11 and 12 are connected to the tubular portion by spaced elongated webs 14 which may be of any required number, and of a length, structure and arrangement suitable to the formation of assemblies of different sizes. The spaced elongated webs extend from each end of the guide body 10 to the respective coupling elements 11 and 12 and are axially arranged with respect to the same.

Referring to Fig. 2 the internally threaded box forming the lower coupling element is shown in section, the threads 15 receiving the threaded pins C on the adjacent rod extremity B. The threaded box is elongated so that the end of the pin is spaced from the end wall 16. This end wall 16 defines the lower end of a reduced threaded bore 17 axially aligned with the internally threaded adjacent coupling box. It will be noted that the annular flange 18 defining the lower end of the threaded pin C is of a diameter and construction to abut against the lower face 19 of the coupling element 12 to limit the movement of the threaded pin C and space the inner end of this pin a short distance from the wall 16 thus providing and defining a chamber 21 at this point. A port 22 extends radially from the chamber 21 through the wall of the coupling body 12 having a tangential relation to the inner face of the chamber as more clearly shown in Fig. 4.

Referring to Fig. 1 reference character M indicates the shank of a pin threaded at m and terminating at its lower end in a conical guide portion m'. The pin M is provided with a conventional threaded upper pin structure identical with the pin structure C of the sucker rod and is adapted to be screwed into the lower threaded box of the coupling element 12. The conical extremity m' acts as a guide when inserting the element into a broken structure as illustrated in Fig. 1, permitting the centering of this element and the engagement of the threads m with the threads formed within the reduced bore 17.

In actual use a plurality of the combined sucker rod couplings and guides are utilized and where one is ruptured due to long use the rupturing takes place through the weakest point which is through the elongated webs 14. When such a rupture occurs a threaded pin m is substituted

for the broken section and the sucker rod assembly lowered to permit the threading of the pin into the reduced threaded bore 17. The lower section which was severed by the rupture can then be readily removed and a new element substituted. The radial bore or perforation 22 communicating with the chamber 21 eliminates the accumulation of sediment, scale or sand and permits such material to be slushed out during the normal operation of the assembly. By virtue of this perforation 22 the threaded bore 17 is always clear and thus a quick connection may be made with the pin M.

It will be noted in the formation of the present structure that the lower coupling element 12 is of greater length than the upper coupling member 11, and this elongation is essential to provide a body structure of ample length to accommodate the reduced threaded bore 17 which receives the fishing pin M. The relative length of the lower coupling with reference to the upper coupling may be varied according to the relative size of the assembly.

What I claim is:

1. A paraffin scraper section for a sucker rod assembly comprising two connecting members secured together by longitudinal ribs, an annular body having angular shearing faces connecting said ribs intermediate their ends, one of said connecting members having an outer threaded bore and a spaced inner axially formed reduced bore, and a port in the wall separating the spaced threaded bores.

2. A sucker rod coupling comprising, a tubular body portion formed with angular cutting faces, spaced ribs extending longitudinally from both ends of the body portion, the ends of said ribs terminating in coupling elements, one of said elements being provided with an internally threaded box portion, a longitudinally threaded bore extending axially of said threaded box and spaced therefrom, and a port formed in the wall below said threaded bore.

3. A paraffin scraper section for a sucker rod string comprising upper and lower connecting members rigidly secured together solely by longitudinal ribs having their outer surfaces lying in a cylindrical surface, an annular body portion connecting the ribs intermediate their ends and flush with their external surfaces, the lower of said connecting members having a longitudinally threaded bore opening downwardly and an upper spaced axially arranged reduced threaded bore opening upwardly and a port formed in the wall intermediate the threaded portions.

4. A paraffin scraper section for a sucker rod string comprising upper and lower connecting

members rigidly secured together solely by longitudinal ribs having their outer surfaces lying in a cylindrical surface, an annular body portion connecting the ribs intermediate their ends and flush with their external surfaces, the lower of said connecting members being elongated and having formed therein spaced axially aligned internally threaded portions the lower portion opening downwardly and the upper opening upwardly, and a drainage opening in the wall spacing 10 said threaded portions.

5. A paraffin scraper section for a sucker rod string comprising upper and lower connecting members rigidly secured together solely by longitudinal ribs having their outer surfaces lying 15 in a cylindrical surface, an annular body portion connecting the ribs intermediate their ends and flush with their external surfaces, the lower of said connecting members having a longitudinally threaded bore opening downwardly and an upper 20 spaced axially arranged reduced threaded bore opening upwardly and a port formed in the wall intermediate the threaded portions.

6. A sucker rod coupling comprising, a tubular body portion, circumferentially spaced ribs extending longitudinally from both ends of the tubular body portion, the ends of the ribs terminating in rod connecting members for engaging the ends of adjacent rod sections, the lower one of said connecting members having a threaded 30 bore for receiving a rod section and having a reduced threaded bore thereabove for engaging a fishing tool.

7. A sucker rod coupling comprising, two rod connecting members secured together by longitudinal ribs, the lower member having an outer threaded bore for receiving a rod, and having an inner reduced threaded bore thereabove for receiving a fishing tool.

8. A coupling as set forth in claim 7, and a 40 settling chamber between the two bores.

9. A coupling as set forth in claim 7, and a settling chamber separating the two bores, and an escapement port leading from the chamber.

10. A sucker rod coupling including upper and 45 lower rod connecting members, an intermediate tubular member, the connecting members being spaced from and supported by the intermediate tubular member by spaced webs, said webs being so constructed and arranged as to permit free 50 passage of fluid through said tubular member, and between said tubular member and said rod connecting members, said lower connecting member having an outer threaded bore for receiving a rod, and an inner reduced threaded bore for receiving a fishing tool.

JEREMIAH J. FITZPATRICK.
